LATCHING AND COCKING DEVICE FOR AIR RIFLES

David A. Hills and Ronald W. Joyce, Rogers, Ark., and Robert Borden Willett and James F. Watkins, Tulsa, Okla., assignors, by mesne assignments, to Victor Comptometer Corporation, Chicago, Ill., a corporation of Illinois

Filed Dec. 16, 1964, Ser. No. 418,746
14 Claims. (Cl. 124—15)

This invention relates generally to rifles, and particularly to an improved cocking and latching assembly for air rifles.

Rifles of the type to which the present invention relates in general utilize a movable piston for displacing compressed air to project shot through a tube mounted within the gun barrel. To effect this operation, the piston is cocked or spring loaded by the user and held in this position until it is released by the user and the gun discharged as by pulling the trigger.

For the particular reason that many of these rifles find use among adolescents, it is of the utmost importance that every precaution be taken to insure safe operation and to prevent inadvertent or accidental rifle discharge after cocking. At the same time, these rifles must be constructed so as to permit relatively easy cocking. However, care must be taken not to unduly complicate the rifle mechanism since both excessive weight and cost seriously detract from the marketability of the rifle.

An important object, therefore, of the present invention is an air rifle cocking and latching device adapted to minimize the effort needed to cock the rifle and to virtually eliminate the possibility of inadvertent or accidental rifle discharge.

A further object of the present invention is a cocking and latching device of the above character wherein the cocking assembly is positively locked against further movement after spring loading by the latching assembly until the rifle is discharged.

A further object of the present invention is a cocking and latching device of the above character wherein the latching assembly is biased to maintain proper positioning thereof throughout all phases of rifle operation.

A further object of the present invention is a cocking and latching device of the above character which is relatively inexpensive to manufacture, sturdy and simple in construction, light in weight and reliable and safe in operation.

Further objects and advantages will become more apparent from a consideration of the following detailed description and claims taken in conjunction with the drawings in which:

FIGURE 1 is a side view of an air rifle embodying the principles of the present invention;

FIG. 2 is an enlarged sectional view of a portion of FIG. 1;

FIG. 3 is an enlarged fragmentary view of the latching assembly shown in FIG. 2 with the parts in the latched position;

FIG. 4 is a view similar to FIG. 3 illustrating the latch and plunger assemblies immediately after firing and before the trigger has been released;

FIG. 5 is a view similar to FIGS. 3 and 4 showing the parts being cocked; and

FIG. 6 is a sectional view of the structure of FIG. 3 taken along the line 6—6 thereof.

Broadly described, the present invention includes a cocking lever manually movable in a forward direction to engage the rifle plunger while tensioning an auxiliary spring, and thereafter movable in a rearward direction carrying the plunger with it, thereby loading the main

2

spring while the auxiliary spring pays out to assist in loading the rifle main spring. A latch assembly normally biased away from the cocking lever is engaged by the plunger when it is moved rearwardly with the cocking lever to bias it toward and into latching engagement with the cocking lever. The cocking lever, latch assembly and plunger are so interrelated that the entire cocking assembly is positively locked against further movement until the rifle has been discharged.

Referring now more specifically to the drawing, and especially FIGS. 1 and 2, an air rifle embodying the principles of the present invention is seen to include a receiver assembly, generally indicated at 11, and a barrel assembly 13 removably fixed to the receiver by a screw 15 and extending forwardly therefrom. An operating forearm 17 is slidably disposed on the barrel assembly 13 for movement from a position adjacent the receiver 11, shown in FIGS. 1 and 2, to a position forwardly thereof and back to the position adjacent the receiver to cock the rifle.

Finally, the rifle of the present invention includes a stock indicated generally at 19 extending rearwardly from the receiver 11 and fixed thereto to simulate a real cartridge or bullet firing rifle.

The rifle of the present invention is designed to propel BB's or other conventional projectiles through a barrel tube 21 mounted within a false barrel 23. To effect this, a piston tube 25 is moved rapidly along the barrel 21 into engagement with a projectile positioned adjacent one end thereof. In addition, compressed air is forced through the piston tube 25 and out its end against the projectile during its movement along the barrel 21 and the combined effect is to propel the projectile rapidly through the barrel 21 and out the forward end thereof. The projectiles are singularly positioned in the usual manner within an opening 27 in a feed cylinder 29 which communicates with the rear end of the barrel 21 from a feed tube 31 in preparation for each shot.

The piston tube 25 is fixed to one end of a plunger assembly 32 including a plunger case 33 and plunger head 35 by a pin 37. The plunger head 35 is slidably disposed within a contractible chamber 39 formed in the false barrel 23 between a sealing washer 41, positioned between the plunger head 35 and the plunger case 33 and movable therewith, and a sealing washer 43 adjacent the feed cylinder 29. The piston tube 25 has an aperture 45 forwardly of the plunger head 35 so that as the plunger assembly 32 moves in a forward or right-hand direction as viewed in the drawings to contract the chamber 39, air from within this chamber is forced through the opening 45 out the end of the piston tube 25 and into the barrel 21.

Forward movement of the plunger assembly 32 and piston tube 25 is effected through a relatively strong main compression spring 47 caged between a washer 49 mounted on the plunger assembly adjacent the sealing washer 41 and a plate 51 fixed within the false barrel 23. Thus, as the plunger assembly is moved rearwardly, or in a left-hand direction as viewed in the drawings, the main spring 47 is compressed between the washer 49 and the fixed plate 51. When the rifle is fired, the plunger assembly 32 is released and the main spring 47 forces the plunger assembly and piston tube 25 forwardly to propel the projectile through the barrel 21.

One of the features of the present invention is an improved easily operated cocking assembly for compressing the main spring 47. Thus, a longitudinally movable, channel-shaped, cocking lever 53 has a pair of laterally spaced lug members 55 welded or otherwise suitably fixed thereto extending upwardly therefrom and provided with rearwardly facing shoulders 57 adapted to engage a pair of laterally spaced forwardly facing shoulders 59 on a clip member 61 suitably fixed to the plunger case 33. As shown

in FIG. 2, the forward end of the cocking lever 53 pivotally carries a pinion gear 63 through a pin 64. The gear 63 is positioned for operative engagement with a downwardly facing rack gear 65 fixed to the false barrel 23 and with a similar upwardly facing driving rack gear 67 fixed to the forearm 17 by a pair of forearm screws 69, each of which freely extends through an elongated slot 70 in a respective one of a pair of guides 72. The forearm 17 is movable from its normal, rearward position illustrated in FIGS. 1 and 2 to a forward position where these screws 69 engage the forward end of the slots 70. As the forearm moves forwardly, the driving rack 67 rotates the pinion gear 63 in a counterclockwise direction as viewed in FIG. 2, causing it to walk in a right-hand or forward direction along the fixed rack 65. This, in turn, causes the cocking lever 53 to move forwardly, through the pivot pin connection 64, to a position where the shoulders 57 on the lugs 55 engage behind the shoulders 59 on the clip 61. See FIG. 5. Thereafter, the forearm 17 is moved rearwardly causing clockwise rotation of the gear 63 and rearward movement thereof. This effects rearward movement of the cocking lever 53 and through the lugs 55 and clip 61, moves the plunger assembly 32 rearwardly thereby compressing the main spring 47 as described above.

To be effective in propelling projectiles from the barrel 21 rapidly and with reasonable accuracy, the main spring 47 is a relatively strong compression spring and, as a result, difficult to compress. For this reason, air rifle cocking assemblies often are designed with relatively complex lever assemblies and/or differential rack and pinion arrangements to assist in cocking the plunger assembly. To assist in cocking the plunger assembly 32 of the present device to compress the main spring 47, a relatively long spring 71 has one end fixed to the cocking lever 53 at a location near the forward end thereof and the other end fixed as by a pin 73 to the rearward end of the rifle stock 19. The spring 71 is, at all times, under tension thereby preventing the cocking assembly components from rattling as a result of play. When the forearm 17 is moved forwardly, thereby moving the gear 63 and the cocking lever 53 forwardly as described above, the effect is to tension or load the spring 71. Thus, rearward movement of the forearm 17, the cocking lever 53 and the plunger assembly after the shoulders 57 and 59 are engaged is assisted by the spring 71 as it pays out. In other words, as the tension in the spring 71 is relieved, the main spring 47 is loaded in compression thereby reducing the force required to be exerted by the user during the cocking sequence. Contrasted with a cocking assist device using a differential gear arrangement and an identical main spring, the main spring 47 of the present device is compressed the same amount with a lesser amount of forearm movement than required in the differential gear device.

The tension spring 71 serves the additional function of exerting a resilient upward force on the cocking lever 53 tending to pivot it in a clockwise direction about the pin 64 to insure proper engagement between the shoulders 57 and 59 on the lugs 55 and the clip 61, respectively, during the cocking sequence and until the rifle is discharged. Thus, by fixing the spring 71 to the cocking lever 53 from beneath the lever and near its forward end, a force component in an upward direction results thereon. When the cocking lever 53 is moved forwardly, engagement between the clip 61 and a cam surface 75 formed on each of the lugs 55 moves the cocking lever downwardly against the biasing force of the spring 71 until the shoulders 57 are adjacent the shoulders 59 at which time the spring 71 moves the cocking lever upwardly as shown in FIG. 5. For convenience, a butt plate 74 is removably fixed to the rearward end of the stock assembly 19 by screws 76 for access to the spring 71 and its mounting 73.

Another feature of the rifle of the present invention is a novel latching and release assembly which includes a sear 77 and trigger lever 79 pivotally mounted independently within the receiver 11 upon a pivot pin 81. As perhaps

best shown in FIG. 3, the sear 77 has a downwardly extending rearwardly facing shouldered portion 83 adapted to be received within an opening 85 intermediate the lugs 55 and to engage a rearwardmost wall 87 thereof. A single torsion spring 89 is mounted on a pin 91 fixed in the receiver 11 and has one end positioned to engage an end wall 93 of the stock 19 and the other end fixed to the forward end of the sear 77. Normally, the effect of the spring 89 is to bias the sear 77 in a counterclockwise direction around the pivot pin 81 and away from the cocking lever 53. However, when the plunger assembly 32 is moved rearwardly with the cocking lever 53 during the cocking sequence, a downwardly facing surface 95 formed on a notched portion of the clip 61 engages the spring 89 thereby forcing it and the sear downwardly and positioning the shoulder 83 in engagement with the wall 87. See FIG. 3. Thus, the sear 77 retains the cocking lever 53 in its rearward position which in turn holds the plunger 33 in its rearward position as long as the clip surface 95 engages the spring 89. In addition, since the pinion 63 remains engaged with the racks 65 and 67, further movement of the forearm 17 is precluded until the cocking lever is released from the sear which is not effected until the rifle is fired. This naturally eliminates the danger of inadvertent or accidental firing by providing a positive lock for the entire cocking and plunger assemblies and, additionally, it provides a positive indication to the user that the rifle is cocked.

The rifle is fired by pulling rearwardly on a trigger 97 formed integral with or otherwise fixed to the trigger lever 79. This pivots the trigger lever 79 in a clockwise direction around the pivot pin 81 and causes a lower surface 99 of the trigger lever 79 to engage an end portion 101 of the cocking lever 53 and moves it downwardly against the upward biasing force of the spring 71 until the shoulders 57 on the lugs 55 move away from the shoulders 59 on the clip 61 whereby the plunger 33 is released and is thrust forwardly by the main spring 47. See FIG. 4. Thereafter, when the trigger 97 is released, the torsion spring 89 pivots the sear 77 in a counterclockwise direction thereby freeing the cocking lever 53 for forward movement by the forearm 17 and the next cocking sequence. Counterclockwise pivotal movement of the sear 77 brings it into engagement with an overhanging lip 103 formed on the trigger lever 79 and pivots it and the trigger 97 counterclockwise about the pin 81 until the trigger 97 engages an abutment surface 105 on the receiver 11.

Thus, by the present invention, there is provided an improved air rifle cocking and latching assembly adapted for easy handling and foolproof operation.

While a preferred embodiment of the present invention has been illustrated and described above in detail, various additions, substitutions, modifications and omissions may be made thereto without departing from the spirit of the invention as encompassed by the appended claims.

What is claimed is:

1. In an air rifle having a plunger slidably disposed within a barrel and first spring means biasing said plunger in a forward direction, a cocking device for said plunger comprising:
a cocking lever movable forwardly and rearwardly adjacent said plunger,
second spring means having one end fixed to said cocking lever and tending to bias said cocking lever in a rearward direction,
manually actuatable means for moving said cocking lever in a forward direction loading said second spring means and thereafter in a rearward direction, said cocking lever including means effective when said cocking lever is in its forward position engaging said plunger and carrying it rearwardly therewith thereby loading said first spring means when said cocking lever is moved in a rearward direction.

2. In an air rifle having a plunger slidably disposed within a barrel and first spring means biasing said plunger in a forward direction, a cocking device for said plunger comprising:

a cocking lever movable forwardly and rearwardly adjacent said plunger,

second spring means having one end fixed to said cocking lever and tending to bias said cocking lever in a rearward direction,

a pinion rotatably carried by said cocking lever adjacent the forward end thereof,

a first rack fixedly mounted within said rifle and engaging said pinion,

a second rack engaging said pinion opposite said first rack,

manual means for moving said second rack longitudinally of said rifle in a forward direction rotating said pinion and moving said cocking lever also in a forward direction loading said second spring means and thereafter in a rearward direction.

said cocking lever including means effective when said cocking lever is in its forward position engaging said plunger and carrying it rearwardly therewith thereby loading said first spring means when said cocking lever is moved in a rearward direction.

3. In an air rifle having a plunger slidably disposed within a barrel and first spring means biasing said plunger in a forward direction, a cocking device for said plunger comprising:

a cocking lever movable forwardly and rearwardly adjacent said plunger,

second spring means having one end fixed to said cocking lever and tending to bias said cocking lever in a rearward direction and toward said plunger,

manually actuatable means for moving said cocking lever in a forward direction loading said second spring means and thereafter in a rearward direction, said cocking lever including means effective when said cocking lever is in its forward position engaging said plunger and carrying it rearwardly therewith thereby loading said first spring means when said cocking lever is moved in a rearward direction,

and manually actuatable means for moving said cocking lever away from said plunger thereby releasing said plunger for movement by said first spring means.

4. In an air rifle having a plunger slidably disposed within a barrel and first means biasing said plunger in a forward direction, a cocking and latching device for said plunger comprising:

a cocking lever movable longitudinally forwardly and rearwardly adjacent said plunger,

second spring means having one end fixed to and tending to bias said cocking lever in a rearward direction, manually actuatable means for moving said cocking lever first in a forward direction loading said second spring means and thereafter in a rearward direction,

said cocking lever including means effective when said cocking lever is in its forward position engaging said plunger and carrying it rearwardly therewith thereby loading said first spring means when said cocking lever is moved in a rearward direction,

and releasable latch means engageable with said cocking lever when in its rearward position.

5. In an air rifle having a plunger slidably disposed within a barrel and first spring means biasing said plunger in a forward direction, a cocking and latching device for said plunger comprising:

a cocking lever movable longitudinally forwardly and rearwardly adjacent said plunger,

second spring means having one end fixed to and tending to bias said cocking lever in a rearward direction,

manually actuatable means for moving said cocking lever first in a forward direction loading said second spring means and thereafter in a rearward direction,

said cocking lever including means effective when said cocking lever is in its forward position engaging said plunger and carrying it rearwardly therewith thereby loading said first spring means when moved in a rearward direction,

latch means pivotally mounted adjacent said cocking lever,

latch biasing means normally biasing said latch means in a first direction away from said cocking lever, said plunger including means operatively engaging said latch biasing means when moved rearwardly with said cocking lever thereby moving said latch means in a second direction opposite said first direction to engage and maintain said cocking lever in its rearward position, and means for releasing said cocking lever from said latch means.

6. In an air rifle having a plunger slidably disposed within a barrel and first spring means biasing said plunger in a forward direction, a cocking and latching device for said plunger comprising:

a cocking lever movable longitudinally adjacent said plunger,

second spring means having one end fixed to and tending to bias said cocking lever in a rearward direction,

manually actuatable means for moving said cocking lever first in a forward direction loading said second spring means and thereafter in a rearward direction, said cocking lever including means effective when said cocking lever is in its forward position engaging said plunger and carrying it rearwardly therewith thereby loading said first spring means when moved in a rearward direction,

latch means pivotally mounted adjacent said cocking lever, torsion spring means having one end fixed to and normally biasing said latch means in a first direction away from said cocking lever,

said plunger including means operatively engaging said torsion spring means adjacent said end when moved rearwardly with said cocking lever thereby moving said latch means in a second direction opposite said first direction to engage and maintain said cocking lever in its rearward position,

and means for releasing said cocking lever from said latch means.

7. In an air rifle having a plunger slidably disposed within a barrel and first spring means biasing said plunger in a forward direction, a cocking and latching device for said plunger comprising:

a cocking lever movable longitudinally adjacent said plunger,

second spring means having one end fixed to and tending to bias said cocking lever in a rearward direction, pinion means rotatably carried by said cocking lever adjacent the forward end thereof,

first rack means fixedly mounted within said rifle and engaging said pinion means,

second rack means engaging said pinion means opposite said first rack means,

manual means for moving said second rack means longitudinally of said rifle in a forward direction rotating said pinion means and moving said cocking lever also in a forward direction loading said second spring means and thereafter in a rearward direction, said cocking lever including means effective when said cocking lever is in its forward position engaging said plunger and carrying it rearwardly therewith thereby loading said first spring means when said cocking lever is moved in a rearward direction,

and releasable latch means engageable with said cocking lever when in its rearward position.

8. In an air rifle having a plunger slidably disposed within a barrel and first spring means biasing said plunger in a forward direction, a cocking and latching device for said plunger comprising:

a cocking lever movable longitudinally adjacent said plunger,
 second spring means having one end fixed to and tending to bias said cocking lever in a rearward direction,
 5 pinion means rotatably carried by said cocking lever adjacent the forward end thereof,
 first rack means fixedly mounted within said rifle and engaging said pinion means,
 second rack means engaging said pinion means opposite said first rack means,
 manual means for moving said second rack means longitudinally of said rifle in a forward direction rotating said pinion means and moving said cocking lever also in a forward direction loading said second 10 spring means and thereafter in a rearward direction, said cocking lever including means effective when said cocking lever is in its forward position engaging said plunger and carrying it rearwardly therewith thereby loading said first spring means when moved in a rearward direction,
 latch means pivotally mounted adjacent said cocking lever,
 15 latch biasing means normally biasing said latch means in a first direction away from said cocking lever, 20 said plunger including means operatively engaging said latch biasing means when said plunger is moved rearwardly with said cocking lever thereby moving said latch means in a second direction opposite said first direction to engage and maintain said cocking lever in its rearward position,
 25 and means for releasing said cocking lever from said latch means.
 9. In an air rifle having a plunger slidably disposed within a barrel and first spring means biasing said plunger in a forward direction, a cocking and latching device for said plunger comprising:
 a cocking lever movable longitudinally adjacent said plunger,
 30 second spring means having one end fixed to and tending to bias said cocking lever in a rearward direction, pinion means rotatably carried by said cocking lever adjacent the forward end thereof,
 first rack means fixedly mounted within said rifle and engaging said pinion means,
 second rack means engaging said pinion means opposite said first rack means,
 manual means for moving said second rack means longitudinally of said rifle in a forward direction rotating said pinion means and moving said cocking 35 lever also in a forward direction loading said second spring means and thereafter in a rearward direction, said cocking lever including means effective when said cocking lever is in its forward position engaging said plunger and carrying it rearwardly therewith thereby loading said first spring means when moved in a rearward direction,
 latch means pivotally mounted adjacent said cocking lever,
 40 torsion spring means having one end fixed to and normally biasing said latch means in a first direction away from said cocking lever,
 said plunger including means operatively engaging said torsion spring means adjacent said end when said plunger is moved rearwardly with said cocking lever thereby moving said latch means in a second direction opposite said first direction to engage and maintain said cocking lever in its rearward position,
 45 and means for releasing said cocking lever from said latch means.
 10. In an air rifle having a plunger slidably disposed within a barrel and first spring means biasing said plunger in a forward direction, a cocking and latching device for said plunger comprising:

a cocking lever movable longitudinally adjacent said plunger,
 latch means pivotally mounted adjacent said cocking lever,
 latch biasing means normally biasing said latch means in a first direction away from said cocking lever, 5 second spring means having one end fixed to said cocking lever and tending to bias said cocking lever in a rearward direction and toward said latch means, manually actuatable means for moving said cocking lever in a forward direction loading said second spring means and thereafter in a rearward direction, said cocking lever including means effective when said cocking lever is in its forward position engaging said plunger and carrying it rearwardly therewith thereby loading said first spring means when moved in a rearward direction,
 said plunger including means operatively engaging said latch biasing means when said plunger is moved rearwardly with said cocking lever thereby moving said latch means in a second direction opposite said first direction to engage and maintain said cocking lever in its rearward position,
 and trigger means having a portion engageable with said cocking lever and adapted to move said cocking lever away from said plunger thereby freeing said plunger for forward movement.
 11. In an air rifle having a plunger slidably disposed within a barrel and a first spring means biasing said plunger in a forward direction, a cocking and latching device for said plunger comprising:
 a cocking lever movable longitudinally adjacent said plunger,
 latch means pivotally mounted adjacent said cocking lever,
 latch biasing means normally biasing said latch means in a first direction away from said cocking lever, 25 a second spring means having one end fixed to said cocking lever and tending to bias said cocking lever in a rearward direction and toward said latch means, pinion means rotatably carried by said cocking lever adjacent the forward end thereof,
 first rack means fixedly mounted within said rifle and engaging said pinion means,
 second rack means engaging said pinion means opposite said first rack means,
 manual means for moving said second rack means longitudinally of said rifle in a forward direction rotating said pinion means and moving said cocking 30 lever also in a forward direction loading said second spring means and thereafter in a rearward direction, said cocking lever including means effective when in its forward position engaging said plunger and carrying it rearwardly therewith thereby loading said first spring means when moved in a rearward direction, said plunger including means operatively engaging said latch biasing means when said plunger is moved rearwardly with said cocking lever thereby moving said latch means in a second direction opposite said first direction to engage and maintain said cocking lever in its rearward position,
 and trigger means having a portion engageable with said cocking lever and adapted to move said cocking lever away from said plunger thereby freeing said plunger for forward movement.

12. In an air rifle having a plunger slidably disposed within a barrel and a first spring means biasing said plunger in a forward direction, a cocking and latching device for said plunger comprising:
 a cocking lever movable longitudinally adjacent said plunger,
 latch means pivotally mounted adjacent said cocking lever,

a second spring means having one end fixed to said cocking lever and tending to bias said cocking lever in a rearward direction toward said latch means, torsion spring means having one end fixed to and normally biasing said latch means in a first direction away from said cocking lever, 5
 manually actuatable means for moving said cocking lever in a forward direction loading said second spring means and thereafter in a rearward direction, said cocking lever including means effective when said cocking lever is in its forward position engaging said plunger and carrying it rearwardly therewith thereby loading said first spring means when moved in a rearward direction, 10
 said plunger including means operatively engaging said torsion spring means adjacent said end when said plunger is moved rearwardly with said cocking lever thereby moving said latch means in a second direction opposite said first direction to engage and maintain said cocking lever in its rearward position, and trigger means having a portion engageable with said cocking lever and adapted to move said cocking lever away from said plunger thereby freeing said plunger for forward movement. 15
 13. In an air rifle having a plunger slidably disposed within a barrel and a first spring means biasing said plunger in a forward direction, cocking lever means and sear latching means for said plunger comprising: 20
 a cocking lever movable longitudinally adjacent said plunger, 25
 manually actuatable means for moving said cocking lever first in a forward direction and thereafter in a rearward direction, said cocking lever means effective when in its forward position engaging said plunger and carrying it rearwardly therewith thereby loading said first spring means when moved in a rearward direction, 30
 sear latch means pivotally mounted adjacent said cocking lever, 35
 latch biasing means normally biasing said sear latch means in a first direction away from said cocking lever, 40

said plunger including means operatively engaging said sear latch biasing means when said plunger is moved rearwardly with said cocking lever thereby moving said sear latch means in a second direction opposite said first direction to engage and maintain said cocking lever in its rearward position, and means for releasing said cocking lever from said sear latch means. 14. In an air rifle having a plunger slidably disposed within a barrel and a first spring means biasing said plunger in a forward direction, cocking lever means and sear latching means for said plunger comprising: 15
 a cocking lever movable longitudinally adjacent said plunger, 20
 manually actuatable means for moving said cocking lever first in a forward direction and thereafter in a rearward direction, said cocking lever means effective when in its forward position engaging said plunger and carrying it rearwardly therewith thereby loading said first spring means when moved in a rearward direction, 25
 sear latch means pivotally mounted adjacent said cocking lever, 30
 torsion spring means having one end fixed to and normally biasing said sear latch means in a first direction away from said cocking lever, 35
 said plunger including means operatively engaging said torsion spring means adjacent said end when said plunger is moved rearwardly with said cocking lever thereby moving said sear latch means in a second direction opposite said first direction to engage and maintain said cocking lever in its rearward position, and means for releasing said cocking lever from said sear latch means.
